UNITED STATES PATENT OFFICE.

HARRY J. LYONS, OF GENEVA, ILLINOIS, ASSIGNOR TO GENEVA HEATER COMPANY, OF CHICAGO, ILLINOIS, A CORPORATION OF ILLINOIS.

STORAGE WATER HEATER.

Application filed March 20, 1924. Serial No. 700,530.

To all whom it may concern:

Be it known that I, HARRY J. LYONS, a citizen of the United States, residing at Geneva, in the county of Kane and State 5 of Illinois, have invented certain new and useful Improvements in Storage Water Heaters, of which the following is a specification.

This invention pertains to water heaters 10 adapted for household and other similar purposes and more particularly to the type of heater comprising a tank in which the water is both heated and stored for use.

The primary purpose of this invention is 15 to provide a heater which will be economical to manufacture and which will be efficient in operation so that it may be operated at a low cost, and which will maintain a considerable quantity of water at a predetermined heated temperature so that it is immediately available for use when required.

Other objects and advantages of this invention should be readily understood from the following description when considered 25 in connection with the accompanying drawings.

Referring to the drawings:

Fig. 1 is a vertical central sectional view 30 through a heater embodying my invention. Fig. 2 is a transverse sectional view taken on the line 2—2 of Fig. 1; and

Fig. 3 is a similar view taken on the line 3—3 of Fig. 1.

Referring now to the drawings more in 35 detail, reference character 5 indicates generally a storage tank formed of boiler material or other suitably heavy metal, adapted to contain water under pressure and wherein the water is both heated and stored for 40 use. The tank is surrounded by a jacket 6 formed of suitable heat insulating material, and the whole structure is carried upon a base plate 7, supported by suitable legs 8. The tank 5 is formed to provide a central 45 flue and heating chamber 9 extending centrally through the tank in a vertical direction from end to end thereof. The bottom 11 of the tank is spaced upwardly a considerable distance above the base plate 7 to 50 provide a combustion chamber 12, access to which may be had at one side of the chamber through a door 13.

The base plate 7 is provided with a central opening 14 through which air to support 55 combustion flows to the burner 15, which is

mounted directly over the opening. A mixing tube 16, in which air and gas are mixed before being delivered to the burner, extends laterally from the burner, and a gas supply pipe 17 projects into the outer end 60 of said tube. A control valve 18 is interposed in the pipe 17 and the opening and closing of this valve is controlled by a thermostat 19 projecting into the storage tank so as to be influenced by the temperature 65 of the water therein. The upper end of the gas supply pipe 17 is connected with the gas main, or any other suitable source of gas supply, and a shutoff valve 21 is preferably interposed in this pipe so that gas to the 70 burner may be entirely shut off when desired. A pipe 22 connected with the gas supply pipe above the thermostat valve 18, terminates in a pilot burner 23 located in proximity to the main burner 15 for the 75 purpose of lighting said main burner when gas is admitted thereto. The pilot light pipe 22 has a valve 21' therein so that the gas supplied to the pilot light may be shut off when desired.

For the purpose of facilitating the heating of the water in the tank and for the further purpose of establishing a circulation of such water during the heating thereof, a pipe or large tube 24 is disposed within the tank around the central flue 9 and is spaced from said flue a limited distance to provide within the pipe and around the flue a heating and circulating passage or chamber 25. The lower end of this pipe is supported upon a circulating baffle 26 in the form of a plate having a central opening communicating with the space 25, the perimeter of this plate or baffle being spaced from the surrounding walls of the tank and the plate being supported upon a plurality of suitable legs 27, so that the baffle is spaced away from and above the bottom 11 of the tank. When the tank is full of water, the water in the space 25 which is heated from the flue 9, flows upwardly and is delivered into the upper portion of the tank through openings 28. At the same time the colder water flows downwardly around the perimeter of the baffle 26, then inwardly over the bottom 11 and thence upwardly within the tube 24.

For the purpose of utilizing to the maximum degree the heat units rising through the flue 9 from the burner in the combus- 110

tion chamber, I have provided within and above the flue baffles, which will now be described. From Fig. 1 it will be observed that the upper end of the tank 5 terminates some little distance beneath the heat insulating top 29 of the structure. Within the space between the top 29 and the upper end of the tank a baffle plate 31 is supported intermediate the top and the tank by suitable stays 32. Since the diameter of the plate 31 is less than the diameter of the heater structure, a passage is formed over the top of the tank, then upwardly around the edges of the baffle 31, and then inwardly beneath the top 29 through which the products of combustion issuing from the flue 9 pass before they are delivered through the discharge opening 33 formed in the center of the top 29. The deflection of the products of combustion around this baffle results in the heating of the upper end of the tank and thus increases the efficiency of the heater.

For the purpose of baffling the flow of the products of combustion through the flue 9, I have arranged within said flue a plurality of baffles 34, two being shown in the present instance for illustrative purposes, which baffles are carried by a rod 35 depending from the center of the baffle plate 31.

In the operation of the heater water is supplied to the tank to keep the same full through a supply pipe 36 connected with the city water main, or other source of supply, and having its delivery end extending downwardly into the tank to a point preferably near the bottom of the tank. The pilot burner 23 being lighted, if the temperature of the water surrounding the thermostat 19 be lower than the temperature for which the thermostat is set, the thermostat will contract, opening the fuel control valve 18 and admitting a supply of fuel to the burner 15 where it is ignited by the pilot burner. The products of combustion rising from the burner, heat the bottom 11 of the tank and as they pass upwardly through the flue 9, the walls of the flue are heated and as the products are deflected around the baffle plate 31, the top of the tank is also heated. The heat units transferred through the bottom 11 and the walls of the flue 9 to the surrounding water, cause the water to flow upwardly in the space 25 around the flue, the heated water being delivered into the top of the tank through the openings 28. The colder water flowing to the bottom of the tank passes inwardly beneath the baffle 26 where it enters the space 25, and in turn becomes heated and flows upwardly. A circulation of water within the tank is therefore established, which facilitates the heating of the water. When the water surrounding the thermostat becomes heated to a predetermined temperature, the expansion

of the thermostat closes the valve 18, thus cutting off the supply of fuel to the main burner. A tank full of heated water is therefore maintained ready for use and when part of it is drawn off and other water flows in through the pipe 36, the thermostat being cooled by the inflowing water, contracts and opens the valve 18, thus again turning on the main burner.

The heater therefore operates automatically to maintain a tank of heated water at the desired temperature ready for immediate use. The baffles which deflect and retard the escape of the heated products of combustion result in a high efficiency of the heater, which efficiency is still further increased by the circulating pipe 24 and the circulating baffle 26, which ensure a circulation of the water within the tank.

It is believed that the construction, operation and many of the advantages of this invention will be apparent from the foregoing without further description, and it should be manifest that the structural details illustrated and described may be varied within considerable limits without departing from the essence of this invention as defined in the following claims.

I claim:

1. In a water heater the combination of a tank having a vertical flue extending therethrough, a combustion chamber beneath the tank, a burner in said chamber, a circulating baffle disposed within and spaced above the bottom of said tank, a pipe surrounding said flue and communicating at its lower end with the space beneath said baffle, and means within and above said flue for baffling the products of combustion rising from said burners.

2. In a water heater the combination of a bottom plate provided with a central opening, legs supporting said plate, a jacket carried by said plate, a tank surrounded by said jacket, said tank terminating short of the upper and lower ends of said jackets, a flue extending vertically through said tank, a main burner supported upon said plate over said opening, a pilot burner in proximity to said main burner, a pipe in said tank surrounding said flue and spaced therefrom, a circulating baffle spaced above the bottom of said tank, baffles in said flue, and a baffle plate above the flue.

3. In a water heater in combination, a water tank provided with a center flue, a fuel burner beneath said flue, a pipe in said tank surrounding and spaced from said flue and communicating only at the top and bottom thereof with the interior of said tank, and a single baffle plate extending radially outward about and from the lower end of said pipe and in a plane substantially parallel to the plane of the bottom of said tank to provide a passage for circulation of water

inwardly from the walls of said tank toward said pipe and upwardly therethrough.

4. In a water heater in combination, a circular water tank provided with a center flue extending between the ends thereof, a fuel burner beneath the lower end of said flue, a circular partition in said tank surrounding and spaced from said flue, openings in said partition at the top thereof for communication with the interior of said tank, said partition being spaced slightly above the bottom of said tank for water circulation between said tank and the space interiorly of said partition, and a single circular baffle plate extending radially outward about and from the lower end of said partition and in a plane substantially parallel to the plane of the bottom of said tank to provide a passage for

circulation of water inwardly from the walls of said tank beneath said baffle toward and upwardly through the space between said partition and said flue.

5. A water heater, comprising a boiler, a flue located therein between the top and bottom thereof, a water circulating pipe surrounding said flue and communicating with the upper and lower portions of the boiler, and a single horizontally disposed circular partition in the boiler surrounding the flue a short distance above the bottom of said boiler forming a water chamber communicating with the water circulating pipe and with the water space exterior of said water circulating pipe.

HOWARD A. JOHNSON.

inwardly from the walls of said tank toward said pipe and upwardly therethrough.

4. In a water heater in combination, a circular water tank provided with a center flue extending between the ends thereof, a fuel burner beneath the lower end of said flue, a circular partition in said tank surrounding and spaced from said flue, openings in said partition at the top thereof for communication with the interior of said tank, said partition being spaced slightly above the bottom of said tank for water circulation between said tank and the space interiorly of said partition, and a single circular baffle plate extending radially outward about and from the lower end of said partition and in a plane substantially parallel to the plane of the bottom of said tank to provide a passage for

circulation of water inwardly from the walls of said tank beneath said baffle toward and upwardly through the space between said partition and said flue. 20

5. A water heater, comprising a boiler, a flue located therein between the top and bottom thereof, a water circulating pipe surrounding said flue and communicating with the upper and lower portions of the boiler, and a single horizontally disposed circular partition in the boiler surrounding the flue a short distance above the bottom of said boiler forming a water chamber communicating with the water circulating pipe and with the water space exterior of said water circulating pipe. 25 30

HOWARD A. JOHNSON.

Certificate of Correction.

It is hereby certified that the signature of the patentee at the end of the printed specification in Letters Patent No. 1,536,613, granted May 5, 1925, upon the application of Harry J. Lyons, of Geneva, Illinois, for an improvement in "Storage Water Heaters," was erroneously printed as "Howard A. Johnson," whereas said name should have been printed as *Harry J. Lyons*; and that the said Letters Patent should be read with this correction therein that the same may conform to the record of the case in the Patent Office.

Signed and sealed this 22d day of September, A. D. 1925.
